REFRIGERATOR LATCH

William F. Dart, Mason, Mich.

Original application March 8, 1934, Serial No. 714,717. Divided and this application October 16, 1935, Serial No. 45,368

2 Claims. (Cl. 292—5)

This application is a division of my co-pending application, Serial No. 714,717 filed Mar. 8, 1934, now Letters Patent No. 2,051,132, dated August 18, 1936.

5 This invention relates to a closure for refrigerators and like containers of the above stated character which will permit the refrigerator to be fully opened when desiring to remove or replace articles from the food compartment, and 10 10 which will permit exposure of the ice cube chamber when desiring to obtain ice, so that atmospheric temperatures will not readily enter the food compartment and unnecessarily raise the temperature therein, consequently permitting the 15 refrigerator to be more economically operated and the temperature within the refrigerator more evenly maintained, assuring a better preserving of food products over a longer period of time.

The primary object of the invention is the 20 provision of inner and outer doors mounted for simultaneous opening and closing of the refrigerator, and capable of being operated so that the inner door may remain closed for the closing of the food compartment during the opening of 25 the outer door, while at the same time giving admittance to the ice cube chamber.

Referring to the drawings:

Figure 1 is a fragmentary perspective view illustrating a refrigerator equipped with a door construction constructed in accordance with my 30 invention.

Fig. 2 is a fragmentary horizontal sectional view showing the inner and outer doors latched together and occupying door-closing position.

35 Fig. 3 is a similar view showing the inner and outer doors moved simultaneously to an open position for exposing the interior of the refrigerator.

Fig. 4 is a similar view showing the outer door 40 occupying an open position while the inner door occupies a closed position and exposing the rack of the inner door so that articles may be readily placed in and removed therefrom.

Fig. 5 is a fragmentary sectional view showing 45 the means of latching the inner and outer doors together and also a spring catch for aiding in maintaining the inner door in a closed position when the outer door is released therefrom and swung to an open position.

50 Fig. 6 is a detail sectional view taken on the line 6—6 of Fig. 5.

Fig. 7 is a disrupted view showing one of the hinges.

55 Fig. 8 is a fragmentary view showing the latch for securing the outer door in closed position

and the finger piece of the latch employed for securing the inner and outer doors together.

Fig. 9 is a fragmentary view showing one of the hinges.

Referring in detail to the drawings, the numeral 1 indicates a conventional type of refrigerator wherein the cooling unit is shown at 2 and is of the type to freeze ice cubes or blocks, the remaining interior of the refrigerator being employed for the storage of food products and 10 the like. Heretofore when obtaining ice from the freezing or cooling unit, it was necessary to expose the entire interior of the refrigerator to atmospheric temperatures, causing an unnecessary raising of the temperature of the refrigerator and increasing the cost of operation and maintenance, and to overcome these disadvantages my invention is employed and is in the 15 form of a closure hingedly mounted to the refrigerator, and includes inner and outer doors 2 and 3, both supported to the refrigerator 1 by hinges 4, capable of permitting the doors to swing simultaneously or one independent of the other. The inner door 2 is shaped so that when in closed position, it will expose a freezing or cooling unit 2 while the food compartment is closed to the atmosphere. The outer door 3 is of the 20 chambered or flanged construction forming upon the interior face thereof a chamber or space 5 to receive a rack 6, supported by the outer face 25 of the inner door when said doors engage with each other, or when latched together, which will be hereinafter more fully described. The rack 6 may be employed for various articles not needing 30 very low temperatures for their preservation, and when the outer door 3 is opened independently of the inner door, the rack 6 becomes fully 35 exposed so that articles may be readily placed in and removed therefrom.

A spring catch 7 is carried by the refrigerator 40 to engage with the inner door for aiding in retaining the latter in a closed position when the outer door is swung open. The catch 7 is of a conventional type, that is employing a spring pressed ball engageable with a notch or socket 45 formed in the inner door.

The outer door is equipped with a conventional type of latch 8 to engage with a keeper 9 on the refrigerator 1 for retaining the outer door in a closed position and is operable by a handle 10 50 when desiring to free the outer door for movement into an open position.

A keeper 11 is carried by the outer face of the inner door and enters the chamber 5 when the inner and outer doors are in abutting engage- 55

ment and is engaged by a latch 12 carried by the outer door where said doors will be fastened together. The latch consists of a member 13 journaled in a bracket 14 carried by the outer door 5 and has formed upon its inner end an angularly disposed projection or arm 15 to engage with the keeper 11.

Slidably mounted in the outer wall of the outer door is a tubular finger-piece 16, which slidably 10 receives the member 13 and the latter is provided with spiral grooves 17, engaged by a lug 18 formed on the finger piece 16, whereby endwise movement of the finger piece will impart rotation to the member 13. A coil spring 19 is interposed 15 between the bracket 14 and the inner end of the finger piece 16 for normally urging the latter in one direction or in a direction to cause rotation of the member 13 for positioning the arm 15 in engagement with the keeper 11. A manual movement 20 of the finger piece in an opposite direction causes reverse rotation of the member 13 to disengage the arm 15 from the keeper 11.

It is preferable that the finger piece 16 be located in close proximity to the handle 10 of the 25 latch 8 so that a person operating the handle 10 to free the outer door may also operate the latch 12 to free said outer door from the inner door, permitting the latter to remain in closed position.

Ordinarily in opening a compound door such as 30 that described it is often desirable to first expose the rack in the inner door, and to then swing the inner door out to expose the shelves in the main compartment in the refrigerator. Consequently it is desirable to have the inner door free to swing 35 independently of the outer door. Therefore, while the outer door is closed the user may operate the latching devices so as to permit such independent operation of both doors.

To accomplish the foregoing action, the operator 40 presses the finger piece 16 and unlatches the outer door which may then be swung open to its

extreme position as illustrated in Fig. 5, while the inner door may be swung to an independently open position as also illustrated in Fig. 5.

Having thus described my invention, what I claim as new and desire to secure by Letters 5 Patent, is:

1. Latching means for a pair of doors comprising a latch for the outer of the doors having a pivoted actuating handle, a pull connection having interlocked and released positions extending 10 through said outer door connecting with a keeper on an inner door, a finger piece for said pull connection to the inner door positioned adjacent said actuating handle so that the same may be operated when the handle is manually grasped, all 15 with one hand, and a double acting fastener for said inner door for releasing said inner door when said pull connection is in interlocked position.

2. Latching means for a pair of doors comprising a latch for the outer of the doors having a 20 pivoted actuating handle, a pull connection having interlocked and released positions extending through said outer door connecting with a keeper located on an inner door, a finger piece for said pull connection to the inner door positioned adjacent 25 said actuating handle so that the same may be operated when the handle is manually grasped, all with one hand, and a double acting fastener for said inner door for releasing said inner door when said pull connection is in interlocked position, 30 said pull connection comprising in combination with said keeper on said inner door, a tubular extension provided with a spiral groove, a lug formed on said finger piece and engaging within said spiral groove, a bracket carried by said outer door within which said tubular extension is rotatably journaled, and resilient means extending from said bracket and urging said finger piece 35 outwardly so as to maintain said finger piece in non-interlocking position.

WILLIAM F. DART.
